UNITED STATES PATENT OFFICE

150,832

DESIGN FOR A CLOCK

Estelle M. Fenzenbock, North Hollywood, Calif.

Application November 14, 1947, Serial No. 142,526

Term of patent 3½ years

(Cl. D42—7)

To all whom it may concern:

Be it known that I, Estelle M. Fenzenbock, a citizen of the United States, residing at North Hollywood, Los Angeles County, State of California, have invented a new, original, and ornamental Design for a Clock, of which the following is a specification, reference being had to the accompanying drawing, forming a part thereof.

Fig. 1 is a perspective view of a clock showing my new design; and

Fig. 2 is a rear view of the clock shown in Fig. 1.

I claim:

The ornamental design for a clock, substantially as shown.

ESTELLE M. FENENBOCK.
